GRADING MACHINE

James W. Johnston, Manchester, N. H., assignor
to North American Holding Corporation, Syra-
cuse, N. Y., a corporation of New York

Application April 16, 1935, Serial No. 16,572

11 Claims. (Cl. 271—59)

This invention relates to grading machines of the kind which grade died-out blanks of leather, such as cut soles, in accordance with their thickness as determined by a detecting or measuring device.

The principal object of the invention is to provide means to guide the blanks in a straight path as they pass through the feeding and measuring rolls and prevent them from swerving or being displaced edgewise.

Although the invention is of broader application, I will describe it, for the purpose of illustration, as applied to a grading machine of the type shown in the Cogswell Patents No. 1,686,487, dated October 2, 1928 and No. 1,820,010, dated August 25, 1931.

In the accompanying drawings,

Fig. 1 is a top plan view of a grading machine embodying the invention;

Fig. 2 is a plan view of one of the extension guide bars hereinafter described;

Fig. 3 is a side elevation of said guide bar;

Fig. 4 is a plan view of the other guide bar;

Fig. 5 is an enlarged section on line 5—5 of Fig. 1;

Fig. 6 is a sectional detail on line 6—6 of Fig. 5;

Fig. 7 is a sectional detail on line 7—7 of Fig. 5;

Fig. 8 is a section on line 8—8 of Fig. 1;

Fig. 9 is a diagrammatic view showing in side elevation the relation of the guide rails to each other and to the feeding and measuring rolls; and

Fig. 10 illustrates a modification showing mechanism for adjusting all the guide rails in unison.

At the front of the machine is a magazine or hopper which holds the soles or other blanks S to be graded in a stack resting on a table or shelf 10. The blanks are automatically fed by the usual feeding mechanism one at a time from the bottom of the stack to the detecting or measuring and feeding rolls 15 and 16 by which the blanks are measured and propelled through the machine. The measuring and feeding rolls 15 and 16 are continuously driven in the direction indicated by the arrows in Fig. 9. As each blank passes between the rolls 15 and 16 the thickness of its thinnest part is detected and determined and the lower, yielding roll 16 acts through the usual mechanism to set the pointer 17 relatively to the dial 18 of the usual indicator.

The blank is discharged from the rolls 15 and 16 upon the central work-supporting track 31,

which is narrower than the blanks, formed on top of the bed plate 19. When the blank is removed by the operator from underneath a trip (not shown), the feeding mechanism is set in motion by which another blank is fed from the bottom of the stack of blanks in the magazine to the rolls 15 and 16.

For a more detailed description of the construction and operation of the machine, which has been only briefly and generally outlined above, reference may be had to either of the two patents aforesaid. Machines of this character are well known in the art and contain many parts which are not material to the present invention and which it is therefore not necessary to describe in explaining the present invention.

Each roll 15 and 16 comprises, as usual, two sections which are adjustably mounted on shafts. The two sections of each roll are separated at the middle by an intervening space so that only the side marginal portions of the blank are engaged by the rolls, since it is the usual practice to grade soles and the like according to the thickness of the thinnest measurement of the marginal areas, especially the marginal areas of the forepart of a sole. It is therefore important that the sole pass through the machine with the median line of its forepart parallel to its direction of movement and approximately midway between the two sections of each roll.

In the machines as heretofore constructed there is nothing to prevent the blanks, after leaving the magazine and while being propelled through the machine by the feeding and measuring rolls 15 and 16, from swerving edgewise, with the result that the median line of the blank sometimes swings laterally in one direction or the other instead of maintaining a straight path always parallel with the direction of movement of the blank. Consequently it sometimes happens that the desired marginal areas of the blank are not correctly traversed by the roll sections and imperfect grading results.

Machines of the kind illustrated are largely used for grading cut soles. As is well understood, cut soles are asymmetrical or crooked in shape as illustrated in Fig. 1 by the sole S shown in dotted lines, the heel part being offset laterally with relation to the forepart and at a substantial angle to the median line of the forepart. The guiding of such irregularly shaped soles, both toward and away from the measuring and feeding rolls, involves problems which are not encountered in the guiding of blanks whose shape is regular and symmetrical. Moreover a sole of this kind

tends, while passing through the rolls, to swerve in the direction of its general curvature or offset. For example, a left sole, such as that illustrated at S in Fig. 1, has its heel part curved or offset toward the left, when viewed from the toe end, and in passing through the machine tends to swerve toward the left or counterclockwise. Similarly a right sole which is offset in the opposite direction tends to swerve toward the right or clockwise.

The present invention has to do with guides for preventing such swerving movements and for insuring the travel of the sole through the machine in a substantially straight path with the median line of the forepart of the sole at all times substantially parallel to the direction of travel.

The magazine in which the soles are stacked on the shelf 10 includes a rear wall 11 fixed to the frame of the machine, a front wall 12 also fixed to the machine with provision for adjusting it to accommodate blanks of different lengths, a pair of side walls 13 on the wall 11 and a pair of side walls 14 on the wall 12, the side walls also being adjustable to accommodate blanks of different widths and shapes.

Mounted on the shelf 10 at the bottom of the magazine and in advance of the measuring and feeding rolls 15 and 16 is a pair of parallel guide rails 20 and 20^a. The guide rail 20, as shown in Figs. 1 and 5, is a piece of angle iron having fixed to its bottom side a block or lug 24, which extends downwardly through a slot 25 formed in the shelf 10. Near its lower end the lug 24 has a hole formed with a left-hand thread, into which is threaded one end of a spindle 26 similarly having a left-hand thread to engage the thread in lug 24. The other guide rail 20^a is similarly constructed of a length of angle iron with a block or lug 27 fixed to its bottom side and projecting downwardly through a slot 28 in the shelf 10. The hole in lug 27 is made with a right-hand thread and engages the other end of the spindle 26, which is provided with a right-hand thread. The angle iron guide rails 20 and 20^a are so positioned that their horizontal flanges rest on the shelf 10 and extend outwardly in opposite directions while their upstanding flanges, which are preferably inclined a little outwardly, constitute the guides for the blanks resting on the shelf 10.

For a given size of soles the magazine walls and the side guides 20 and 20^a are so adjusted and set that a line drawn on the sole from a point bisecting the toe end of the sole to a point bisecting the narrowest part of the shank, is coincident with the median line of the machine. When the parts are so set, as will be apparent from Fig. 1, the guide rail 20^a will be a little farther from the median line of the machine than the guide rail 20, since a left sole is a little wider or more protuberant on that side of said median line than on the other side. These conditions are reversed in the case of a right sole. The side guide rails engage only the wide ball portion of the sole and therefore are relatively so set that the distance between them is approximately the same as the width of the ball of the sole.

In order to adjust the two guide rails 20 and 20^a toward and from each other to fit them to the width of the ball of the sole the spindle 26 is manually rotated by means of a handle 29 provided at one end thereof. A single adjustment serves for both right and left soles, since after the proper width adjustment has been made the two guides may be laterally adjusted or shifted

together as a pair, when changing from right to left soles, or vice versa, without changing the width adjustment.

The lateral adjustment or displacement of the two guide rails in unison as a pair in order to offset the pair in one direction or the other from the median line of the machine, depending on whether right soles or left soles are to be graded, is accomplished by shifting the spindle 26 endwise in one direction or the other. To limit the displacement of the spindle 26 toward the right, as viewed in Fig. 5, a stop nut 30 is provided, adjustably mounted on the spindle 26 and secured in its adjusted position by a lock nut 31. The engagement of the stop nut 30 with an abutment 32 fixed to the under side of shelf 10 limits the endwise movement of the spindle in that direction. A collar 33 adjustably mounted on the spindle 26 at the opposite side of the abutment 32 limits the endwise movement of the spindle 26 toward the left, as viewed in Fig. 5, by engagement with the abutment 32.

In order to hold the spindle 26 in its adjustment at either limit of its endwise movement, I provide a latch 34 pivotally mounted on the abutment 32 at 35 and having a depending handle 36 by means of which the latch can be manually raised to free the spindle 26 when it is to be shifted endwise. When the spindle 26 is at the limit of its endwise movement toward the right, as shown in Fig. 5, the latch 34 engages the inner side of the collar 33 and prevents the shifting of the spindle toward the left. When the spindle is at the limit of its movement toward the left, the collar 33 engages the abutment 32 and the latch 34 engages the outer side of the collar 33 and prevents movement of the spindle toward the right. The latch 34 is braced and steadied by a slotted post 34^a, fixed to the under side of the shelf 10, the free end of the latch 34 working up and down in the slot in post 34^a. By adjustment of the stop members 30 and 33 on the spindle 26 the extent of the offset of the pair of guide rails 20 and 20^a may be varied.

In connection with the guide rails 20 and 20^a I provide a pair of extension guide bars 21 and 21^a (Figs. 1, 2, 3 and 4), one for use when operating upon right soles and the other for use when operating upon left soles, although with some styles of blanks the two might be used simultaneously. When operating upon a left sole of the kind shown at S in Fig. 1, the extension guide bar 21^a is attached to the guide rail 20^a, the extension guide bar for the other guide rail 20 being omitted to leave a clear space between the end of the guide rail 20 and the measuring rolls for the laterally offset heel end of the blank. Similarly, when right soles are to be graded the extension guide bar 21 will be attached to the guide rail 20 and the opposite extension guide bar 21^a will be omitted. It will be understood that the bottom edge of the rear wall 11 of the magazine and the bottom edges of the side walls 13 of the magazine are spaced sufficiently above the surface of shelf 10 to provide room not only for the passage of the blanks but for the positioning and adjustment of the extension guide bars beneath said walls.

The front end of each extension guide bar 21, 21^a, is provided with a clip for detachably securing the guide bar to its guide rail. As herein shown, this clip consists of a jaw member formed by bending or folding the end of the guide bar back upon itself thus providing a U-shaped loop which acts as a clip to embrace the end of the

guide rail and hold the extension guide bar in position.

At the rear or delivery side of the rolls 15 and 16 I provide a pair of guide rails 22 and 23 for guiding the advance ends of the blanks as they emerge from said rolls.

Each rear guide rail 22 and 23 is a short length of angle iron having an upstanding flange to engage and guide the edge of the sole and a horizontal inwardly extending flange which serves as a ledge or runway for the laterally offset heel end of the blank. As shown in Fig. 9, the horizontal flanges of the guide rails 22 and 23 slope upwardly from the rolls 15, 16, so that they are positioned in substantially the same plane with the top surface of the central work-supporting track 37, which usually inclines upwardly. Fixed to the under side of each rear guide rail 22 and 23 is a block or lug 38 (Figs. 8 and 9) extending downwardly through a transverse slot 39 (Fig. 1) formed in the bed plate 19. Each lug 38 is made with a threaded hole through which extends a threaded spindle 40, rotatably supported near its ends on the frame of the machine. One of these threaded connections consists of right-hand threads and the other consists of left-hand threads whereby the guide rails 22 and 23 may be adjusted toward and from each other by rotating the spindle 40 by means of a handle 41 fixed to one end of the spindle. The spindle 40 is held in position against accidental endwise displacement, but with provision for adjustment, by means of two pairs of nuts 42 and 43, a sleeve 44 being provided between the pair of nuts 43 and the adjacent side of the frame.

In the machine above described the front guide rails 20 and 20^a are adjusted by the spindle 26 and the rear guides 22 and 23 are adjusted by the spindle 40, said two adjustments being independent each of the other. In Fig. 10 a modification is illustrated whereby all four of said guide rails may be adjusted together or in unison. The spindle 26 has fixed thereon a pinion 45 meshing with an elongate gear 46 fast on a short shaft 47. The shaft 47 carries a sprocket wheel 48 which is connected by a sprocket chain 49 with a sprocket wheel 50 fixed on the spindle 40. With this construction the rotation of either spindle acts through the sprocket wheels and chain and gears 45 and 46 to rotate the other spindle to a corresponding extent. When the spindle 26 is shifted bodily endwise, for the purpose above described, the gear 45 will slide longitudinally in the elongate gear 46.

The operation of the machine is as follows. Assume that the magazine is filled with a stack of left soles S and that the front guide rails 20 and 20^a are properly adjusted to the size and shape of the soles as already described. The extension guide bar 21^a is attached to the guide rail 20^a and the sole will occupy the position shown in Fig. 1, where the offset heel end projects laterally beyond the line of the guide 20 and the sole is guided only at the widest part of the ball or forepart of the sole. The rear guide rail 22 is adjusted to an offset position outwardly from the line of the front guide 20 to the line traversed by the outermost tip or edge of the offset heel end of the blank. The rear guide 23 will at the same time be adjusted laterally to a corresponding position appropriate to a corresponding right sole. As the sole is advanced by the feeding mechanism to the rolls 15, 16, the ball of the sole is guided between the front guides 20 and 20^a. As soon as the offset

heel end reaches the offset guide rail 22 the guide rail 22 will prevent any tendency of the advance end (the offset heel) to swing toward the left, and the horizontal ledge of the guide rail 22 will support the offset end in the same plane with the body of the sole which rests upon the track 37. At the same time the extension guide bar 21^a will prevent any tendency of the ball of the sole to swing to the right even though the opposite side of the ball of the sole has passed beyond the guide rail 20, and this condition will prevail until the widest part of the ball of the sole has practically reached the rolls 15 and 16 since the guide bar 21^a extends nearly to said rolls. Bearing in mind that the tendency of a left sole of the common style illustrated is to swerve toward the left or counterclockwise, it will be seen that the guides both in advance of the rolls and at the rear of the rolls so control the path of the blank as to cause it to move in a substantially straight line without swerving as it passes between the measuring and feeding rolls 15 and 16.

In a similar manner a right sole will be guided by the front guides and the rear guide 23, the extension guide bar 21 being applied to the guide rail 20 and the extension guide rail 21^a being omitted.

I claim:

1. In a grading machine, a pair of feeding and measuring rolls, a pair of guide rails in advance of said rolls terminating at their rear ends a substantial distance in front of said rolls, whereby an offset end of the blank being graded may project laterally into the space between the rolls and the rear end of one of the guide rails, and an offset guide rail at the rear of said rolls adapted to guide the offset end of the blank as the blank emerges from said rolls.

2. In a grading machine, a pair of feeding and measuring rolls, a pair of guide rails in advance of said rolls terminating at their rear ends a substantial distance in front of said rolls, whereby an offset end of the blank being measured may project laterally into the space between the rolls and the rear end of one of the guide rails, an extension guide bar detachably secured to the other guide rail and extending rearwardly toward said rolls, and an offset guide rail at the rear of said rolls adapted to guide the offset end of the blank as the blank emerges from said rolls.

3. In a grading machine, a pair of feeding and measuring rolls, a pair of guide rails in advance of said rolls terminating at their rear ends a substantial distance in front of said rolls, whereby an offset end of the blank being measured may project laterally into the space between the rolls and the rear end of one of the guide rails, an extension guide bar detachably secured to the other guide rail and extending rearwardly toward said rolls, and a pair of offset guide rails at the rear of said rolls adapted to guide the offset end of a blank which is offset in either direction as the blank emerges from said rolls.

4. In a grading machine, a pair of feeding and measuring rolls, guide rails in advance of said rolls to guide the blanks in their movement toward the rolls, and a pair of guide rails at the rear of said rolls to guide the blanks as they emerge from said rolls, and means to adjust all four of said guide rails laterally in unison.

5. In a grading machine, a pair of feeding and measuring rolls, a pair of guide rails in advance of said rolls terminating at their rear ends a substantial distance in front of said rolls, whereby an offset end of the blank being measured may

project laterally into the space between the rolls and the rear end of one of the guide rails, an extension guide bar detachably secured to the other guide rail and extending rearwardly toward said rolls, and a pair of offset guide rails at the rear of said rolls adapted to guide the offset end of a blank which is offset in either direction as the blank emerges from said rolls, and means to adjust all four of said guide rails laterally in unison.

6. In a grading machine, a pair of feeding and measuring rolls, a work-supporting track narrower than the blanks being graded and disposed at the rear of said rolls, and a guide rail at the rear of said rolls comprising an upstanding flange and a horizontal ledge extending toward and in the same plane with the surface of the work-supporting track.

7. In a grading machine, a pair of feeding and measuring rolls, a work-supporting track narrower than the blanks being graded and disposed at the rear of said rolls, and a pair of guide rails at the rear of said rolls, one at each side of said track, each guide rail comprising an upstanding flange and a horizontal ledge extending inwardly toward and in the same plane with the surface of the work-supporting track.

8. In a grading machine, a pair of feeding and measuring rolls, a work-supporting track narrower than the blanks being graded and disposed at the rear of said rolls, and a pair of guide rails at the rear of said rolls, one at each side of said

track, each guide rail comprising an upstanding flange and a horizontal ledge extending inwardly toward and in the same plane with the surface of the work-supporting track, and means to adjust said guide rails in unison toward and from the work-supporting track.

9. In a grading machine, the combination with a pair of measuring rolls, of guiding means comprising a guide rail terminating at its rear end a substantial distance in front of said rolls, and an extension guide bar detachably secured to the guide rail and extending rearwardly to a point closely adjacent to said rolls.

10. In a grading machine, the combination with a pair of measuring rolls, of guiding means comprising a guide rail terminating at its rear end a substantial distance in front of said rolls, and an extension guide bar detachably secured to the guide rail by means of a clip on the guide bar adapted to embrace the guide rail, said guide bar extending rearwardly to a point closely adjacent to said rolls.

11. In a grading machine, the combination with a pair of measuring rolls, of guiding means comprising a guide rail terminating at its rear end a substantial distance in front of said rolls, and an extension guide bar having a jaw member at one end adapted to embrace the end of the guide rail for removably attaching the extension bar to the guide rail, said guide bar extending rearwardly to a point closely adjacent to said rolls.

JAMES W. JOHNSTON.
